VALVE LIFTING AND TIMING DEVICE FOR INTERNAL COMBUSTION ENGINES

Application filed May 11, 1928. Serial No. 276,906.

This invention relates to improvements in internal combustion engines and particularly to improvements in the valve control mechanism therefor.

- 5 It is the object of this invention to provide new and improved valve timing and lifting mechanism for internal combustion engines to simplify the construction thereof and to cheapen the manufacture thereof.
- 10 To these ends the invention consists in the novel parts and novel combinations of parts, hereinafter defined in the claims and described in the following specification, made in connection with the accompanying drawings, wherein like reference characters refer to the same or similar parts throughout the various views and, in which,

Fig. 1 is a plan view illustrating an internal combustion engine with the invention applied thereto;

Fig. 2 is a view in side elevation of the engine illustrated in Fig. 1, certain of the parts being broken away and shown in section;

25 Fig. 3 is an illustrative view showing the position of the crank shaft, pistons and valves when the parts of the engine are as shown in Figs. 1 and 2, and

30 Fig. 4 is an illustrative view showing the manner in which a cam disk of the invention may be laid out.

Referring to the drawings, a four cylinder four cycle engine A of the internal combustion type is illustrated, the cylinders of which 35 from left to right, as viewed in the drawings, are numbered 1, 2, 3 and 4. The engine includes the crank shaft 5, connecting rods 6, pistons 7, intake manifold 8, exhaust manifold 9 and valve cages 10. The engine is illustrated as being provided with overhead valves and each cylinder is provided with an intake valve 11 and an exhaust valve 12 adapted to seat within the valve cages 10. The valves 11 and 12 are of common construction and carry, 45 surrounding their valve stems and reacting between the top of the valve cages 10 and washers 13 at the upper end of the valve stems, the coiled springs 14 which are normally adapted to hold the valves closed and seated 50 against the valve seats in the valve cages 10.

The cylinders of the engine illustrated have a firing order of 1, 4, 2, 3, as is illustrated by the positions of the various pistons 7 and the formation of the crank shaft 5 in Fig. 3 of the drawings. The engine thus far described is of standard construction.

Referring now to the present invention, a suitable gear 15 is secured to the left end of the crank shaft 5 and is adapted to drive a horizontally disposed counter shaft 16, 65 suitably journaled in the crank case of the engine, through the gear 17. The shaft 16 extends to adjacent the center of the crank case and through suitable beveled gears 18 and 19, drives a vertical shaft 20 journaled in suitable bearings preferably disposed between the two middle cylinders of the engine. In the drawings, the gears 15, 17, 18 and 19 are of such size and so positioned that the vertical shaft 20 will revolve in a counter-clockwise direction, as viewed in Fig. 1, once, while the crank shaft 5 is revolving four times. The ratio of speed between the crank shaft 5 and the vertical shaft 20 will therefore be four to one. The shaft 20 extends upwardly through the cylinder casing and carries at its upper end a disk 21 having a central hub secured to the upper end of shaft 20 and having a peripheral vertically extending flange. In laying out the surface of the cam disk 21, as is illustrated in Fig. 4, the upper surface of the disk will preferably be divided into eight different equal sectors of approximately 45° each and these different sectors, reading in a clockwise direction starting from the bottom of the disk, as shown in Fig. 4, may be labeled "Intake", "Compression", "Fire", "Exhaust"; "Intake," "Compression," "Fire", "Exhaust." The respective intake, compression, fire and exhaust sectors are diametrically opposed to each other. Each of the intake sectors have formed thereon or secured thereto, upstanding intake cams 22 radially spaced equal distances from the center of the cam disk 21 and accurately arranged relative to the center of the disk and extending through an arc of approximately 45°. Each of the exhaust sectors will have formed thereon, or secured thereto, upstanding exhaust cams 23 which

are spaced from the center of the cam disk 21 equal radial distances which will be unequal to the radial spacing of the intake cams 22 from the center of the cam disk 21, and the said exhaust cams are arcuately arranged relative to the center of the disk and extend through arcs of approximately 45°. It is preferred to utilize a cam disk 21, such as is illustrated, which carries on its surface two intake cams and two exhaust cams and which rotates at one-fourth the speed of the crank shaft of the engine. However, for four cycle engines, the cam disk 21 may be divided into sectors which are any desired multiple of four, whereupon the speed of the disk relative to the speed of the crank shaft will be such that one intake cam and one exhaust cam will pass a given point once, while the crank shaft of the engine makes two complete revolutions. Both the intake and exhaust cams will be provided with comparatively steep inclines at their ends and with substantially flat surfaces midway between their ends. The cams for four cycle engines will be so spaced that an exhaust cam will preferably follow an intake cam three sectors behind the same, as the disk 21 is rotated.

Mounted on the top of the cylinders 1, 2, 3 and 4 and extending upwardly some little distance therefrom, are a plurality of suitable brackets 24 shown as affording bearings for short shafts 25. Journaled on each of the shafts 25 is an intake valve rocker arm 26 and an exhaust valve rocker arm 27. Other means for pivoting the rocker arms may be employed if desired. Each of the intake valve rocker arms 26 will run outwardly from its pivot point to a point immediately over the upper end of an intake valve 11, while each of the exhaust valves 27 will run outwardly from its pivot point immediately over the upper end of one of the exhaust valves 12. Bolts 28, carrying lock nuts 29, are threaded into the outer ends of the intake and exhaust rocker arms and project downwardly therefrom to engage or almost engage the upper ends of the intake and exhaust valves. It will be seen that proper adjustment can be made between the lower ends of the bolts 28 and the upper ends of the exhaust and intake valves by varying the length of extension of the bolts 28 from the lower sides of the outer ends of the rocker arms. The rocker arms 26 and 27 extend inwardly to points immediately over the cam disk 21 and have sockets formed thereon at their inner ends which carry nutted bolts 30 having round heads projecting downwardly from the under sides of the sockets for engagement with the cams 22 and 23. The inner ends of all of the intake valve rocker arms 26 will extend to points above the cam disk immediately over the path which the intake cams 22 will take during their travel, as the disk

21 is rotated, while the inner ends of all the exhaust valve rocker arms will extend to points above the cam disk immediately over the path which the exhaust cams 23 will take during their travel as the disk 21 is rotated. Under normal conditions, the springs 14 will hold the round heads of the bolts 22 at the inner ends of the rocker arms 26 and 27 downwardly to within a short distance from the top surface of the disk 21, so that as the disk is rotated, the intake cams 22 will strike bolt heads 30 on the intake valve rocker arms 26 to rock the same and the exhaust cams 23 will strike the bolt heads 30 on the inner ends of the exhaust rocker arms 27 to rock the same. As the disk 21 revolves, therefore the outer ends of the rocker arms will be depressed to depress the various valves 11 and 12 from their seats in the cages 10. The pivot point about which the rocker arms 26 and 27 may turn is so spaced relative to the ends of the various rocker arms that as the various rocker arms strike the cams 22 and 23, their outer ends will move exactly the same distances relative to each other to open valves 11 and 12 equal distances. In the drawings, the various shafts 25 are illustrated as being so positioned that opposing ends of the respective rocker arms 26 and 27 mounted thereon will be spaced from the axial center of the shafts 25 equal radial distances to cause the outer ends of the rocker arms to move the same distances as the inner ends thereof, when actuated by the cams.

Where the cams 22 and 23 are disposed as illustrated in the drawings, the inner ends of the rocker arms 26 and 27 for each cylinder will be so disposed relative to the center of the disk 21 that the centers of the round heads of bolts 30, situated in the rocker arms will lie in the same radius from the center of the disk 21. The inner ends of the intake and exhaust rocker arms for each cylinder will be circumferentially spaced as to their position over the disk 21 to suit the various timing conditions of the particular engine whereon used. Where the firing order of the cylinders of the engine is 1, 4, 2, 3, as in the engine illustrated in the drawings, the inner ends of the rocker arms for cylinder 2 will preferably be set at approximately 90° behind the position of the inner ends of the rocker arms for cylinder 1, so that when the rocker arms for cylinder 1 are disposed, as shown, over an intake sector of disk 21, the rocker arms for cylinder 2 will be disposed over a fire sector. The inner ends of the rocker arms for cylinder 3 will preferably be set at approximately 225° behind the position of the inner ends of the rocker arms for cylinder 1 and the inner ends of the rocker arms for cylinder 4 will preferably be set at approximately 315° behind the position of the inner ends of the rocker arms for cylinder 1, so that when the rocker arms for cylinder 1 are disposed, as shown, over

an intake sector of disk 21, the rocker arms same. In the six cylinder engine, the various for cylinder 3 will be disposed over a compression sector of the intake and exhaust rocker sector of the disk and the rocker arms arms will be set so that the various rocker for cylinder 4 will be disposed over an exhaust sector. The arrangement of the arms will be approximately 30° from each other 70 illustrated for a four cylinder, four cycle engine on the cam disk 21. For an eight cylinder engine having a firing order of 1, 4, 2, 3 will be engine, preferably two cam disks will be provided, the most convenient. It would be found for each set of four cylinders and 75 would be possible, however, to situate the cams on one disk will be set $22\frac{1}{2}^\circ$ behind the inner ends of the rocker arms for cylinder 1, the cams on the other disk, whereupon the position of the inner ends of the rocker arms for cylinder 2 will be the same as shown for cylinder one, and to position the rocker arms for cylinder 3 and four either 45° or 225° . Similarly, two cam disks will be provided and the 80 and 135° or 215° respectively, behind the position of the cams on one disk will preferably be set 15° 85 position of the inner ends of the rocker arms for cylinder 5 and six either 45° or 225° . Similarly, by varying the position that the inner ends of the rocker arms for different cylinders will 90 be set at multiples of 15° angles to each other, the arms for each cylinder will take relative to the word multiples as here used also including each other circumferentially of the disk 21, in divisions. 95 By situating various rocker arms at different angular positions relative to each other, the invention may be applied to internal combustion engines having an irregular number of cylinders, such as three cylinder, five cylinder, seven cylinder, etc. engines. 100 By situating various rocker arms over the disk 21, it is thought that the application of the invention to one and two cylinder engines will be obvious from the above description. By 105 the firing order of the particular engine determined, slight modifications and changes, the invention will be varied to suit the engine. The invention is quite simple and can be applied to practically any type of engine. 110 Similarly, where more or less numbers of intake and exhaust cams than two each, the invention can also be applied to two cycle engines. 115 are provided on the face of the disk and the disk is rotated at less or greater speed than one-fourth the speed of the crank shaft, the angular disposition of the rocker arms for the various cylinders relative to the center of the disk will be varied. In determining what 120 position the inner ends of the various rocker arms of the different cylinders will take, relative to the disk 21, it must first be determined what the position of the various pistons will be at a given time. The inner ends of the 125

4 various rocker arms may then be so positioned relative to the various segments of the disk 21, as illustrated in Fig. 4, that the various valves will be properly positioned for any given condition without departing from the scope of either taking in a charge, compressing a charge, firing a charge or exhausting a charge after the explosion thereof, as determined by the position of the cams 22 and 23 on the disk relative to each other on the disk 21, to suit the timing requirements of the particular engine. In general, it may be stated that the various rocker arms for the various cylinders may be set at multiples of 45° angles to each other, the word multiples for the rocker arms may be varied to vary as here used being also considered to include the amount of movement of the valves etc. divisions.

In applying the invention to a six cylinder engine, the positions of the inner ends of the rocker arms 26 and 27 will be different relative to each other than is the case where the invention is applied to a four cylinder engine; otherwise the parts will remain the same.

5 rotary disk, means for rotating said disk, an intake cam on the face of said disk, an exhaust cam on the face of said disk disposed at a different radial distance from the center
10 5 of said disk than said intake cam, intake valve rocker arms suitably mounted and so disposed relative to said disk that said intake cam will strike the same to rock the arms as the disk is rotated, the intake valve rocker arms for the various cylinders being disposed circumferentially of the disk at multiples of 15° from each other, exhaust rocker arms suitably mounted and so disposed relative to the disk that said exhaust cam will strike
15 the same to rock the arms as the disk is rotated, the exhaust valve rocker arms for the various cylinders being disposed circumferentially of the disk at multiples of 15° from each other, and said exhaust cams being so disposed circumferentially of the disk relative to said intake cams that the exhaust valve rocker arm of each cylinder will be rocked by the exhaust cam after the cylinder has taken three strokes after the intake rocker arm of
20 25 the same cylinder has been rocked by the intake cam.

2. A valve lifting and timing device for internal combustion engines having a plurality of cylinders and an intake and an exhaust valve for each cylinder, comprising a 30 rotary disk, a plurality of intake cams mounted on said disk in symmetrical arrangement relative to the center of the disk, a plurality of exhaust cams mounted on said disk in symmetrical arrangement relative to the center of the disk, said exhaust cams being placed at different radial distances from the center of said disk than said intake cams, an intake valve rocker arm for each cylinder having one end so disposed relative to said disk that said intake cams will strike the same during rotation of the disk to rock the arm, an exhaust rocker arm for each cylinder having one end so disposed relative to the disk that said exhaust cam will strike the same to rock the arm as the disk is rotated, the intake and exhaust rocker arms for each cylinder being so disposed relative to each other that the intake cams will strike the intake rocker arms when the piston of the particular cylinder is three strokes ahead of the point where the exhaust cams will strike the exhaust rocker arm for the particular cylinder.

3. A four cycle internal combustion engine comprising a plurality of cylinders, an intake and exhaust valve for each cylinder, a disk, means for rotating said disk, said disk being divided into a plurality of sectors which total in number multiples of four, an intake cam on every fourth sector, an exhaust cam on every fourth sector, said intake and exhaust cams being radially arranged relative to the center of said disk and being radially spaced from each other, a suitably journaled intake rocker arm for each intake valve, a suitably jour-

naled exhaust rocker arm for each exhaust valve, said rocker arms being respectively so disposed that said intake cams will strike said intake arms to rock the same, and said exhaust cams will strike said exhaust rocker arms to rock the same, as said disk is rotated, said rocker arms being so disposed circumferentially of said disk relative to each other that they will operate to produce a desired timing of the engine, and the intake and exhaust rocker arms for each cylinder being so disposed relative to each other that an exhaust cam will strike an exhaust rocker arm after the disk has rotated three sectors past a sector where an intake cam has struck the intake rocker arm for the same cylinder. 70 75 80

4. A valve lifting and timing device for an internal combustion engine having a plurality of cylinders and an intake and an exhaust valve for each cylinder, comprising a disk, means for rotating said disk at one-fourth the speed of said engine, a pair of radially disposed intake cams mounted on said disk at diametrically opposite points, a pair of radially disposed exhaust cams mounted on 90 said disk at diametrically opposite points, said exhaust cams being radially spaced from said intake cams, a rocker arm for each intake valve suitably pivoted and adapted to be struck by said intake cams to rock the same as said disk is rotated, a rocker arm for each exhaust valve suitably pivoted and adapted to be struck by said exhaust cam to rock the same as said disk is rotated, the intake and exhaust valve rocker arms for each cylinder being so spaced relative to each other that the exhaust valve rocker arm will be actuated after the piston of the cylinder has taken three strokes from the time when the intake rocker arm of the same cylinder has been 95 100 105 rocked.

5. A valve lifting and timing device for a four cycle internal combustion engine having a plurality of cylinders and an intake and exhaust valve for each cylinder, comprising a 110 rotary disk, means for rotating said disk, an intake cam mounted on the face of said disk, an exhaust cam mounted on the face of said disk at a different radial distance from the center of said disk than said intake cam, an intake valve rocker arm for each cylinder of the engine, an exhaust valve rocker arm for each cylinder of the engine, said intake and exhaust valve rocker arms respectively extending over the path taken by the said intake and exhaust cams respectively during rotation of said disk, so that the intake cams will strike the intake rocker arms and the exhaust cams will strike the exhaust rocker arms, and 115 120 125 means for pivotally mounting, said intake and exhaust rocker arms over the intake and exhaust valves of the various cylinders so that as said rocker arms are struck by their respective cams, they will rock to open said 130

intake and exhaust valves the same distance.

6. Valve operating and timing mechanism for an internal combustion engine comprising a rotary disk mounted above the engine head, driving connections between said disk and the shaft of said engine for rotating said disk in synchronism with the rotation of said shaft, intake and exhaust valves for said engine, an exhaust cam on the upper surface of said disk and an intake cam also on the outer surface of said disk spaced at a different radial distance from the center of said disk than said exhaust cam, intake and exhaust valve rocker arms pivoted above the engine head, one end of each of said rocker arms being connected with one of said valves, the opposite end of each of said rocker arms contacting its appropriate cam and actuated thereby, and an elastic element associated with each of said valves to normally close the same and also yieldingly hold the opposite end of its rocker arm in a position to be engaged by its appropriate cam.

7. Valve operating and timing mechanism for an internal combustion engine which has a plurality of cylinders and a longitudinally projectable intake and exhaust valve for each cylinder, comprising a rotary camming disk mounted above the engine head and rotatable on an axis extending substantially parallel with the longitudinal center lines of said valves, a circumferentially positioned exhaust cam on one surface of said disk, and a circumferentially positioned intake cam also on the outer surface of said disk, intake and exhaust valve rocker arms pivoted above the engine head, one end of each of said rocker arms being connected with one of said valves, the opposite ends of said rocker arms contacting said cams and actuated thereby, and elastic elements associated with said valves to normally close the same and also yieldingly hold said rocker arms in position to be engaged by appropriate cams on said disk.

43 In testimony whereof I affix my signature.

FRED W. MARXEN.
